Fig. 3

Fig. 5

Fig. 4

FIG. 1 is a front perspective view of a liquid dispenser for a floor treating machine showing our new design;

FIG. 2 is a rear perspective view;

FIG. 3 is a bottom plan view;

FIG. 4 is a rear elevational view; and

FIG. 5 is a side elevational view thereof.

The dominant features of our design reside in the portion shown in full lines.

We claim:

The ornamental design for a liquid dispenser for a floor treating machine, substantially as shown and described.
